CLAIM

The ornamental design for an abrasive cover for a cleaning tool, as shown and described.

DESCRIPTION

FIG. 1 is a perspective view of a abrasive cover for a cleaning tool showing my new design;

FIG. 2 is an enlarged-scale perspective view of detail II-II in FIG. 1;

FIG. 3 is a side elevational view of FIG. 2, the opposite side being a mirror opposite;

FIG. 4 is an end elevational view thereof, the opposite end being a mirror opposite;

FIG. 5 is a top plan view thereof;

FIG. 6 is a bottom plan view thereof; and,

FIG. 7 is an enlarged-scale perspective view of detail VII-VII in FIG. 4, and showing the backing to the adhesive covering the inner surface in the beginnings of being peeled away.

The broken lines in the drawing represent environmental subject matter that forms no part of the claimed design.
